CLAIM

The ornamental design for a solar powered outdoor light, as shown and described.

DESCRIPTION

FIG. 1 is an isometric view of a solar powered outdoor light showing the new design;

FIG. 2 is a side elevation view thereof, the left, right, front and back elevation views being the same;

FIG. 3 is a top plan view thereof; and,

FIG. 4 is a bottom plan view thereof.

The broken lines shown on the drawings represent environment only and form no part of the claim.
